UNITED STATES PATENT OFFICE

161,189

EXTENSIBLE WRIST WATCH BAND OR
SIMILAR ARTICLE

Leroy H. Knibb, Sabot, Va.

Application May 13, 1948, Serial No. 146,353

Term of patent 14 years

(Cl. D45—4)

To all whom it may concern:

Be it known that I, Leroy H. Knibb, a citizen of the United States residing at Sabot, in the county of Goochland and State of Virginia, have invented a new, original, and ornamental Design for an Extensible Wrist Watch Band or Similar Article, of which the following is a specification, reference being had to the accompanying drawings, forming a part thereof.

Fig. 1 is a top plan view of an extensible wrist watch band or similar article showing my new design;

Fig. 2 is a back view of the same;

Fig. 3 is a side elevational view thereof; and

Fig. 4 is an enlarged fragmentary top plan view of a section of the band.

I claim:

The ornamental design for an extensible wrist watch band or similar article, substantially as shown.

LEROY H. KNIBB.
